UNITED STATES PATENT OFFICE.

JAMES A. GREEN, OF BAYARD, VIRGINIA.

CONCRETE SEPULCHER.

1,373,326.

Specification of Letters Patent. Patented Mar. 29, 1921.

Application filed October 10, 1919. Serial No. 329,786.

To all whom it may concern:

Be it known that I, JAMES A. GREEN, a citizen of the United States, residing at Bayard, in the county of Warren and State 5 of Virginia, have invented certain new and useful Improvements in Concrete Sepulchers, of which the following is a specification.

This invention relates to a concrete sepulcher which will afford not only a very economical, but also a very superior means of 10 burying the dead.

The primary object of the invention is to provide for the construction, *in situ*, of 15 sepulchers or vaults under all weather and climatic conditions in a manner which will permit of the work being properly and effectually carried on without interference and without likelihood of the work being affected by the prevailing conditions if of 20 an inclement nature. Thus the invention contemplates the construction of a concrete or cement sepulcher or vault under conditions favorable to the permanency of the 25 work and to the proper setting of the material of which it is formed.

A further object of the invention is to provide a novel construction of sepulcher and a novel means whereby the head or 30 foot stones or both may be set into place and supported.

In the accompanying drawings:

Figure 1 is a top plan view of a sepulcher constructed in accordance with the invention the cover therefor being omitted;

Fig. 2 is a vertical transverse sectional view therethrough;

Fig. 3 is a vertical longitudinal sectional view with the cover in place;

Fig. 4 is a view similar to Fig. 3 illustrating a more elaborate embodiment of the invention;

Fig. 5 is a vertical transverse sectional view through the structure shown in Fig. 5;

Fig. 6 is a perspective view illustrating a booth which is to be employed in carrying out the invention in inclement weather or under climatic conditions such as would otherwise interfere with the work.

The invention contemplates that the sepulcher shall be constructed *in situ* by the simple operation of troweling and without the use of forms except where the soil conditions are such as to render the use of 50 forms absolutely necessary, as for example in various sandy or loose soils.

In carrying out the invention, as illustrated in Figs. 1, 2 and 3 of the drawings, the grave is dug in the usual manner and of the required dimensions to permit of the 60 sepulcher being built therewith. By troweling and the other well-known operations in the cement worker's art, a sepulcher is constructed within the grave and comprises a bottom 1, side walls 2, end walls 3, 65 and a top or cover which is indicated in general by the numeral 4. The walls 2 and 3 are preferably reinforced by vertically extending ribs indicated respectively by the numerals 5 and 6 which ribs are integral 70 with the outer surfaces of the walls and may be produced by cutting grooves in the side and end walls of the grave. The walls 2 and 3 are further provided at their upper edges with outwardly projecting horizontal 75 flanges or ledges indicated respectively by the numerals 7 and 8, the upper surfaces of which provide a rest for the top or cover of the sepulcher. As illustrated in Fig. 3 of the drawings, this cover may be made 80 in a number of sections indicated by the numeral 9 and of any desired construction although in the illustrated embodiment a number of the sections are assembled edge to edge and extend transversely across the 85 top of the sepulcher. In order to provide a water and air-tight union between the sections comprising the cover 4 and between the cover and the flanges or ledges 7 and 8, any suitable cementitious material may be 90 applied between these contacting surfaces as indicated by the numeral 10 and as clearly shown in Fig. 3. This form of sepulcher is of a simple and inexpensive nature and at the same time it affords a highly effective 95 water- and air-tight incasement for the casket as well as preventing sinking of the grave.

Figs. 4 and 5 of the drawings illustrate a more elaborate embodiment of the invention and in constructing this form of the invention, the sepulcher proper is built up in the manner above described and comprises a bottom 11, side walls 12, and end walls 13 which do not differ materially in their 100 general form from the corresponding parts of the sepulcher previously described. However, in this embodiment each end wall 13 is provided with an upward extension 14 preferably reinforced by one or more ribs 110 15 which may constitute extensions of ribs 16 corresponding to the ribs 6, and each of

these extensions is provided at its top with a supporting ledge or head piece 17 upon which may rest the foundation for the head or foot stone as the case may be. In the 5 said figures the numeral 18 indicates the foundation for the head or foot stone, which foundation may consist of any suitable material and is disposed to rest upon the upper surface of the ledge 17. This foundation 10 is provided upon its under side with a depending anchoring member 19 which is embedded in the soil opposite and spaced from the extension 14 upon which the foundation 18 rests. The base of the head or foot stone 15 as the case may be is indicated by the numeral 20 and the same rests directly upon the foundation 18 and the greater portion thereof is embedded in the soil, the stone, indicated by the numeral 21, being set into 20 or otherwise united with the said base, as clearly shown in Fig. 4.

As before stated the sepulcher whether of the simplest form or of a more elaborate form, is to be molded *in situ* and where the 25 soil is of a clay or heavy nature, this may be done without difficulty or inconvenience and without the employment of mold forms of any kind whatsoever. However, if soil conditions are met with which are unsuitable 30 for this method of construction, mold forms may be employed within the dug grave so as to remedy the difficulty, but as such expedients are commonly resorted to in the art they do not constitute a part of the present 35 invention nor are they illustrated or described.

In order that the above described method 40 of making the sepulcher may be rendered entirely practicable under any and all circumstances, I provide a collapsible booth such as illustrated in a general manner in Fig. 6 of the drawings and indicated by the 45 numeral 22. This booth will be made about four feet wide and eight feet long and will therefore be of ample size to completely cover the larger size of grave. This booth will be employed except when temperature and weather conditions render its use unnecessary. The booth will be built of such 50 height as to afford standing room for a tall workman, and in the comb of the roof of the booth there will be provided a suitable number of hooks indicated by the numeral 23 from which may be suspended ordinary flash 55 lights which will afford ample illumination for carrying on the necessary work in getting the grave ready for the burial. This is all so simple as to be very readily understood but at the same time the language herein embodied is not only an important part 60 of this specification, but is one of the cardinal features of the invention.

In stating all the necessary facts in connection herewith to the end that the status of this invention cannot be misconstrued, I 65 hereby state the necessary means for consummation of the work under prescribed lines. In pursuance of this routine I provide suggestions or instructions for the execution of all ideas as may be good ground 70 work for the necessary details.

The building of this concrete work in the vault and in fact as far up as the freezing process will begin or end, and where the base of the graye stone or monument will rest 75 will preferably be done with an ordinary mason's trowel, but in rare cases, or cases not rare, where the character of the soil must be successfully met I suggest and instruct the employment of any necessary 80 form that will secure a perfect structure of the work. Such form may be of aluminum or other suitable metal, of wood, fiber or any other suitable substance.

After the work is done under a temperature 85 derived from the use of a small oil stove or stoves in very cold weather, the booth must be removed and a thick felt, rubber, or other blanket is to be spread over the grave; but before the cover is put on a very 90 small oil stove must be left in the grave and a small receptacle of water left in the same in order to produce a suitable quantity of steam to prevent freezing in cold weather; and when the blanket is put over the grave 95 and secured by rings with sticks driven in the ground within the rings to secure the same and dirt put around to provide for the retention of the desired temperature, the booth must be put over the whole in case 100 of snowy or rainy weather or in any case if desired.

Having thus described the invention, what is claimed as new is:

1. The method of constructing a sepulcher *in situ* which comprises forming an excavation, forming grooves in the faces of the walls thereof, and applying a layer of plastic material to the walls of the excavation to form the walls of the sepulcher and 105 causing some of the material to enter the said grooves whereby reinforcing ribs will be provided upon the outer surfaces of the sepulcher walls.

2. A concrete sepulcher having one of its 115 walls formed with an offset upward extension to provide a rest for a tomb stone base, and a continuous reinforcing rib formed upon the said wall of the sepulcher and the said extension and reinforcing the parts individually and with relation to each other. 120

In testimony whereof I affix my signature,

JAMES A. GREEN. [L. S.]
